CASING FOR FOOD SERVING EQUIPMENT

Arthur D. Altemiller, Afton, Mo., assignor to
Hercules Steel Products Corporation, Galion,
Ohio, a corporation of Delaware

Application January 7, 1950, Serial No. 7,083
Term of patent 14 years

(Cl. D81—10)

To all whom it may concern:

Be it known that the undersigned, Arthur D. Altemiller, a citizen of the United States, residing at Afton, St. Louis County, State of Missouri, has invented a new, original, and ornamental Design for a Casing for Food Serving Equipment, of which the following is a specification, reference being had to the accompanying drawing, forming a part thereof, in which:

Fig. 1 is a perspective view of a casing for food serving equipment, showing my new design; and Fig. 2 is a rear elevational view thereof.

The essential features of the design reside in the portions shown in full lines.

I claim:

The ornamental design for a casing for food serving equipment substantially as shown and described.

ARTHUR D. ALTEMILLER.
